(57) **CLAIM**

The ornamental design for a dog walking belt, as shown and described.

DESCRIPTION

FIG. 1 is a bottom plan view of the dog walking belt showing my new design;

FIG. 2 is a top plan view of the dog walking belt;

FIG. 3 is a right side view of the dog walking belt;

FIG. 4 is a left side view of the dog walking belt; and,

FIG. 5 is a front perspective view of the dog walking belt while in use.

The broken line showing of an individual in FIG. 5 is included for the purpose of showing an environment of use of the dog walking belt and forms no part of the claimed design.
